ELECTRIC FUSE HOLDER

Charles J. Ward, Philadelphia, Pa., assignor to
 Hugh H. Eby, Inc., Philadelphia, Pa., a corpora-
 tion of Pennsylvania

Application December 24, 1949, Serial No. 134,927

1 Claim. (Cl. 200—133)

1

This invention relates to fuses and more particularly to an improvement in fuse holders and protectors, which are adapted for use in mounting cartridge type fuses for the protection of automobile, lighting, generator and battery circuits or for use in the wiring of other electrical and electronic equipment.

One of the principal objects of the invention is to provide a fuse holder capable of use in an individual wire of a circuit and which will be supported by the wiring, avoiding the necessity for a central fuse panel to which extra lengths of wire must be run. The improved fuse holder may be supplied in assembled form, including a fuse, connector elements, and conductor wires, so that a complete section of wiring, with a protected fuse therein, may be provided for replacement purposes. Alternatively the fuse holder and its component parts, less the conductor wires, may be supplied for use with existing wiring. In such case the existing wiring may be cut at the point where it is desired to insert a fuse, and the fuse holder assembly, which is separable in nature, may then be assembled over the wiring and secured together with its contained fuse electrically connected to the ends of the cut wire.

Another major object of the invention lies in the provision of a multipart fuse holder capable of entirely enclosing a fuse and protecting it from physical injury, access of dirt, grease or oil, and which is further capable of insulating said fuse from short circuiting contact with adjacent metal objects.

Another object of the invention lies in the provision of a multipart fuse holder whose parts are so constructed as to be easily and quickly separable for the replacement of a blown fuse, and which is further capable of being quickly reassembled without need for special tools or time-consuming manual operations.

Still another object of the invention is to provide a multipart holder, for encasing a cartridge type fuse, which will maintain the terminal caps of the fuse in good electrical contact, under pressure, with the connector elements of a wired circuit the same pressure means, within the holder, being also utilized to maintain the parts of the holder in closed and locked condition.

A still further purpose of the invention resides in the provision of a fuse holder and protector of detachably secured casing parts which are of relatively inexpensive molded construction and whose internally assembled metal parts are also inexpensively fabricated by metal stamping and

2

forming operations, avoiding the necessity for costly machining operations.

These and still other objects of the invention will become more apparent from a reading of the description of one embodiment of the invention which has been selected for illustrative purposes and which is shown in the attached drawings.

Referring to the drawings:

Figure 1 is a plan view of a length of wiring capable of use as a circuit section, including a fuse, and the fuse holder assembly with its parts shown in their separated relationship on the wiring as if ready for replacement of the fuse.

Figure 2 is an enlarged plan view of the fuse holder with its casing parts in joined relationship, occupying their normal positions as after insertion of a fuse, and ready for use in the circuit.

Figure 3 is a longitudinal sectional view of the fuse holder taken axially thereof on line 3—3 of Figure 2 and showing the other elements of the fuse holder assembly, including a fuse, in elevation therein.

Figure 4 is a sectional view taken on line 4—4 of Figure 5, and is similar to that shown in Figure 3 but with the casing parts pushed completely together in the manner required prior to disassembly of the fuse holder.

Figure 5 is an elevational view showing part of the fuse holder with the casing members pushed completely together as in Figure 4.

Figure 6 is an elevational view similar to Figure 5 but with the casing parts rotated relative to each other in the manner required for separation and disassembly.

Figure 7 is a sectional view perpendicular to the axis of the fuse holder taken on line 7—7 of Figure 5.

Figure 8 is a sectional view similar to that of Figure 7 taken on line 8—8 of Figure 6 with the casing parts rotated for disassembly.

Figure 9 is an end view of one of the casing parts of the fuse holder taken along line 9—9 of Figure 1.

Figure 10 is an end view of the other of said casing parts taken along line 10—10 of Figure 1.

Figure 11 is an end view of said last named casing part taken along line 11—11 of Figure 1.

Figure 12 is a sectional view taken along line 12—12 of Figure 1.

Figure 13 is a sectional view taken along line 13—13 of Figure 1, and showing one of the projections which is an element of the bayonet type securing means for the casing parts.

The specific embodiment of the invention selected for illustration in the drawings is adapted to hold a fuse 10 of the conventional cartridge

type having an enclosed fuse element 11, and exposed terminals in the form of end caps, these being concealed in the views by the supporting elements of the fuse holder. A pair of cup-shaped connector elements 20 are provided in which the end caps of the fuse are seated for support and electrical contact. Each connector element is preferably a metal stamping having a cup-shaped part of the side wall of which is preferably split lengthwise, as at 21, to enable the fuse cap to spread the side wall of the connector element upon insertion, thus causing the fuse cap to be resiliently grasped under pressure by said split wall of the cup-shaped part of the connector element. A plurality of lugs 22, see Figures 3 and 4, are bent inwardly from the side wall of each connector element, to form the base of the cup, each element including also an end lug 23 which is bent inwardly as at 24 and thence at right angles axially of the cup. The outer extremities of each end lug 23 are adapted to be crimped over a conductor wire end for securement and electrical connection thereto. The illustrated wires of the circuit are referenced 25 in the drawings, and are preferably provided with ring terminals 26 at their outer ends.

A helical coil spring 30 is floatingly carried around one of the conductor wires 25, this spring being preferably formed with flattened end turns to provide planar ends. One end of the coil spring is adapted to abut the base 22 of one of the above described connector elements, while the other end of the coil is adapted to abut an internal shoulder in the fuse holder as will be shortly described.

The fuse holder includes two casing members 40 and 50 which are detachably secured together to completely enclose and protect the fuse 10. The casing members are preferably molded of suitable insulating material and are preferably tubular in shape. Member 40 is provided with an internal bore 41 slightly larger than the diameter of the connector element 21, the member 50 being also provided with a bore 51 of equal diameter. When the casing members are secured together with their respective bores in axial alignment, said members protectively enclose the fuse, the connector elements and the spring described above. The bore 41 communicates with the exterior of casing member 40 through an opening 42 of reduced diameter suitable for passage of wire 25, while a similar reduced passage 52 is provided at the opposite end of casing member 50. The presence of the reduced opening 42 provides a beveled shoulder 43 at the outer end of bore 41. The base lugs 22 and the inturned part 24 of lug 23 of one of the connector elements abuts this shoulder 43 when the fuse holder is assembled. In like manner a square shoulder 53 is provided at the outer end of bore 51 to provide a seat for the outer end of the coil spring 30.

Casing member 40 is provided with a cylindrical surface 44 which is adapted to be telescopically received within an enlarged mouth 54 formed in the end of the bore 51 of the casing member 50. A pair of diametrically opposed bayonet lugs 45-45 project outwardly from the surface 44 of the member 40, while a pair of diametrically opposed grooves 55-55 are formed in the mouth 54 of casing member 50 for axial sliding reception of the lugs 45-45, respectively. In addition, a pair of circumferential slots 56 are provided, which respectively communicate with the grooves 55-55 to form therewith internal bayonet type slots for accommodation of the bayonet lugs 45-45. Each of these slots

extends outwardly and is open to the outer surface of the casing member 50 as shown in Figure 2, rendering the positions and operational movements of lugs 45 visible from the exterior of the fuse holder. Each of the slots 56-56 is provided with an end notch 57 providing a detaining seat for the lug 45 when the latter is in its final inserted position within its accommodating bayonet groove.

Casing member 40 is provided with a portion of enlarged diameter having a grooved or ridged peripheral surface 47 to facilitate finger grasping and prevent slippage. A flattened surface 58, best shown in Figures 2 and 11, facilitates manual gripping of casing member. The two casing members are adapted to be brought together, when grasped on the surfaces mentioned, and portion 44 of one member telescoped into the widened mouth 54 of the other, with the lugs 45 entering slots 55 in the face of the second member. If the casing members 40 and 50 are then pushed together until the end faces 49 and 59 thereof meet they may be relatively rotated for approximately 50° with the lugs 45 traveling in slots 56 until the lugs are in alignment with their detaining notches 57. At this time, release of the casing members causes the lugs 45 to enter the slots 57 under pressure of the compressed coil spring 30. The bayonet lug 45 is then seated in its detaining notch 57 as shown in Figure 2 and rotational disengagement of the bayonet type connection is prevented by pressure of the compressed coil spring 30. When thus locked against rotation, the end faces 49 and 59 are slightly separated as are the complementary bevel surfaces 61 and 62 provided on the casing members 40 and 50 respectively. The presence of these bevels maintains the internal chamber closed against direct entry of foreign objects even though spread slightly.

When it is desired to separate the casing members of the fuse holder in order to inspect the fuse or replace a blown fuse, the two casing members 40 and 50 are again grasped and pushed together to occupy their positions of Figure 5. This movement releases the lug from its detaining notch 57 and permits relative rotational movement of the casing parts. When the lug 45 comes into alignment with the slots 55, pressure of the coil spring will force the two casing members apart and completely separate them, the lug traveling along groove 55. It is then only necessary to pull apart the two exposed connector elements 20 to disengage the blown fuse. A new fuse is then inserted between the connector elements, and the casing members may then be pushed together to surround the fuse and secured in locked relationship in the manner previously described.

It will be noted that the coil spring 30 is compressed between one of the connector elements 20 and the internal shoulder 53 when the pair of casing members are secured and locked together as shown in Figure 3, the fuse being prevented from movement to the left by abutment of the other connector element against shoulder 43. Compression of the coil spring holds the fuse firmly in place with lowered contact resistance, and at the same time exerts a separating force on the two casing members. It is this force which maintains these members locked against relative rotation for disassembly through engagement of lug 45 with the notch 57. Thus, accidental separation of the casing members by shaking, jarring or like movements of the apparatus in which the fuse holder may be mounted is effectually pre-

vented. In order to accomplish their separation it is necessary to wilfully press the two casing members together for release of their locking engagement.

It will be obvious to one skilled in the electrical arts that many modifications may be made in the shape, size, configuration and material of the fuse holder of this invention without departing from its teachings and spirit. The holder and protector may be utilized not only in the types of circuits enumerated above but in any wiring where it would be desirable to fuse individual circuits without lengthening and extending the wires to a central fuse panel. For example, such other application may well be made in the wiring of telephone, telegraph, radio and television apparatus. The holder may be modified to accommodate a plurality of fuses and thus adapted to the fusing of multiple circuits. It is, therefore, desired that the invention not be restricted to the specific construction shown in the drawings but be limited only by the scope and spirit of the appended claim.

What is claimed as new and useful is:

In a fuse holder, a pair of separable members of insulating material conjointly adapted to form a protective casing for a cartridge fuse having end terminal caps, each of said members having extending axially therethrough an elongated bore terminating at its outer end in a hole of a diameter less than that of said bore to provide an internal shoulder at the outer end of each member, cup-shaped contact elements respectively seated in said bores and respectively embracing receiving said end terminal caps for frictional engagement therewith over a wide area, each of said elements having secured thereto a conductor ex-

tending outwardly from each of said casing members through the reduced diameter end hole thereof, a coil spring floatingly embracing one of said conductors and disposed in intervening relation between the contact element of said conductor and the internal shoulder of the member accommodating said last-mentioned contact element, said casing members being respectively provided at their inner connecting ends with interfitting male and female portions adapted to be interconnected and locked together by coacting bayonet and slot means which include an external projection on the male portion of one member and an internal groove on the female portion of the other member, the arrangement being such that upon interlocking assembly of the casing members with the cartridge fuse enclosed thereby the said coil spring exerts its pressure axially against the cartridge fuse to secure the latter between said cup-shaped contact elements and to maintain said casing members locked together.
